UNITED STATES PATENT OFFICE.

ISAAC ALFRED BACKLUND, OF SPOKANE, WASHINGTON.

BOILER-PRESSURE REGULATOR.

1,068,295.

Specification of Letters Patent. Patented July 22, 1913.

Application filed March 4, 1912. Serial No. 681,414.

To all whom it may concern:

Be it known that I, ISAAC ALFRED BACKLUND, a citizen of the United States of America, residing at Spokane, in the county 5 of Spokane and State of Washington, have invented certain new and useful Improvements in Boiler - Pressure Regulators, of which the following is a specification.

This invention pertains to means for regulating the draft through the fire box of a steam boiler to maintain a uniform heat therein for the purpose of keeping up a uniform pressure of steam in the boiler and is made particularly applicable to low pressure 10 boilers. The plan of the device is to take advantage of the expansion and contraction of the steam in the boiler to manipulate the damper or dampers opening and closing the draft through the fire box. I have provided 15 a construction whereby I can regulate either the door to the fire box or the damper in the smoke stack or both.

Other and further objects will be herein-after described and disclosed by the drawings.

I accomplish my purpose by connecting the water in the boiler to a tank, which in turn is connected to levers secured to the fire box door and damper respectively. The expansion of the steam in the boiler forces the water therefrom into the tank. The tank is suspended in such a manner that it has a free vertical action, whereby the weight of the water in the same carries the tank downward and when the water recedes therefrom the tank is carried upward by means of a counter balance.

The mechanism is particularly illustrated in the accompanying drawings, in which—

40 Figure 1, is an end elevation of a boiler and a side elevation of the smoke stack with the apparatus attached, Fig. 2, is a vertical sectional view of the tank and connecting mechanism, Fig. 3, is a broken-away top 45 plan view of the lever extending from the pipe leading to the tank and reaching to the damper shaft, together with a transverse sectional view of the pipe, Fig. 4, is a side view of the same, Fig. 5, is a transverse sectional view of the smoke stack taken on the line 5—5 of Fig. 1 and showing the applica-

tion of the lever attached to the shaft of the damper in the smoke stack to the manipulation of a door in the smoke stack, and Fig. 6, is an end view of the door opening into the fire box and a broken-away view of a lever attached thereto together with the mechanism whereby the door is attached to the boiler.

The boiler 10 has a water tank 11 with a fire box 12 directly underneath the same and of usual construction. The tank 11 has a tap 13 reaching to the water in the same. A passage way for water from the boiler tank 11 is provided through the tap 13, the pipe 14, the valve 15, the flexible tube 16, the vertical pipe 17 to the tank 18. The tank 18 has a tube 19 extending vertically upward from the top thereof, reaching to the interior thereof and open at the top to atmospheric pressure. The tank 18 is also provided with a float 20 of proper specific gravity to float upon the surface of the water 21 that may be in the tank. This float 20 is also adapted to close the opening 22 reaching into the tank 18 from the water supply pipe 17, after the water has entirely receded from the tank and to close the opening 23 reaching from the top of the tank 18 into the tube 19, when the tank is completely filled with water. The pin 24 puncturing the float 20 and reaching into the pipe 17 and the tube 19 serves as a guide to the float to carry the same over the openings 22 and 23 as the tank 18 becomes empty and filled, respectively.

The tank 18 is suspended by the loosely arranged flexible cable 25 attached to the tube 19. Horizontally arranged pins 26 radiate from the pipe 17 as a means whereby the same may be connected to the lever 27. The lever 27 is provided with flexible forks 28 with openings 29 through the same the said openings being adapted to engage the pins 26.

The smoke stack 30 is provided with a damper 31 adapted to fit the same and to revolve upon the shaft 32 and adapted for opening and closing the draft through the smoke stack. The levers 27 and 34 engage the shaft 32 and are made rigid thereon by the thumb-screw 33 passing through the le-

ver hub 35 and bearing against the shaft. The levers 27 and 34 are provided with weights 36 and 37 respectively adapted for adjustment thereon by means of the thumb-screws 38 and 39 respectively.

A door 40 adapted to swing on a hinge 41 opens into the smoke stack 30 and is provided with a hook handle 42 which is in the path of the lever 27. A glass tube 43 open at the top 44 to atmospheric pressure and connected to a pipe 49 which in turn is connected to the pipe 14. A valve 50 being provided at the juncture of the tube 43 and the pipe 49 for convenience serves as a gage to determine the steam pressure in the boiler 10. The water from the tank 11 will rise in the tube 43 and by experimentation and taking the pressure of the steam by other means, a scale can be marked upon the tube 43 to correspond therewith and the same may be relied upon for future purposes. To the lower end of the pipe 17 is secured by a removable pin 45, a lever 46, which is connected at its lower end by means of the pin 47 to the door 48.

The apparatus is operated automatically by the expansion of steam in the boiler 10 as follows: The damper 31 is shown in the drawings as being horizontal leaving an open draft through the smoke stack 30. This position is maintained by the weight 37 upon the lever 34 secured to the damper shaft 32, the weight 36 upon the lever 27 serving as a counter-balance to the empty tank 18 secured to the opposite end of the same lever. While the open draft through the smoke stack 30 is maintained, the door 48 to the fire box 12 is held open by the lever 46 providing for a draft entrance into the fire box. The rings 51 and 52 loosely engage the pipe 17. As shown in the drawings, the drafts are both open and the tank 18 is empty and consequently in an elevated position. As the draft through the fire box increases the rate of combustion of the fuel therein, the water becomes hotter and the steam pressure greater, causing water to pass from the tank 11 through the top 13 to and through the pipe 14, the valve 15, the flexible tube 16, the pipe 17 to the tank 18. After the tank 18 is filled with water the weight thereof is sufficient to overbalance the weights 37 and 38 and the same makes a vertical drop a sufficient distance to close the damper 31 in the smoke stack 30 and to close the door 48 as shown in Fig. 6, thereby completely shutting off the draft through the fire box 12. As the tank 18 drops it carries the end 27^a of the lever 27 downward bringing the end 27^b upward. The end 27^b engages the hook handle 42 of the door 40 and carries the same upward, opening the door 40. This provides an open draft from the boiler room through the smoke stack

serving to clean the room and smoke stack of smoke and dust and to provide a clear atmosphere within the engine room. In case it is desired that the door 48 alone should be operated by this mechanism, then the thumb-screw 33 may be loosened and the damper 31 is not affected by the rise and fall of the tank 18. Or, on the other hand, if it is desired that the damper 31 alone should be operated thereby, then the pin 45 may be removed, releasing the lever 46 from the rise and fall of the tank 18 and the door 48 is not affected thereby. The dotted lines 46^a and 48^a indicate the positions of the parts 46 and 48 respectively when the door 48 is open.

It will thus be observed that I have provided a mechanism whereby the expansion and contraction of the steam in the boiler may be utilized to operate either the door to the fire box or the damper or both at the same time provide for clearing of the atmosphere in the boiler room.

Having thus described my invention, what I claim as new and useful and desire to secure by Letters-Patent, is,

1. In a draft regulator, the combination of a boiler having a flue, a damper in said flue provided with a horizontal shaft, a lever structure disposed on said shaft and adapted to move in a substantially vertical plane and having arm portions extending in opposite directions from said shaft and normally occupying positions at an angle to the vertical, said lever structure also having a third arm portion normally vertically disposed, a weight on one of said first named arm portions, a tank structure on the other of said first named arm portions provided with a flexible connection with the water space of the boiler, a weight on said third arm portion, and means for adjustably connecting said lever structure to said shaft, substantially as described.

2. In a draft regulator, the combination of a boiler having a flue, a damper in said flue provided with a horizontal shaft, a lever disposed on said shaft to move in a substantially vertical plane and having an adjustable weight on one end thereof, a tank structure adjustably mounted on the other end of said lever and having a flexible connection with the water space of the boiler, and means for adjustably connecting said lever on said shaft to vary the action of the tank and weight on said damper, substantially as described.

3. In a draft regulator, the combination of a boiler having a flue provided with damper means opening to the exterior of said flue, an internal damper for said flue having a horizontal shaft, a lever on said shaft adapted to move in a vertical plane and operate said damper means, a weight

on one end of said lever, a tank structure on the other end of said lever having a flexible connection with the water space of the boiler, a boiler damper operatively connected with said tank structure, and means for adjustably connecting said lever to said shaft, substantially as described.

In testimony whereof I affix my signature in presence of two witnesses.

ISAAC ALFRED BACKLUND.
